SIGNORS TO KEELER BRASS COMPANY, OF GRAND RAPIDS, MICHIGAN.

HANDLE FOR DOOR LATCHES.

Application filed May 6, 1924. Serial No. 711,408.

This invention relates to improvements in handles for door latches.

The main object of this invention is to provide an improved handle for door latches, such as automobile doors, which may be provided with the desired finish in silver, nickel or the like, and which is at the same time very economical to produce.

Objects pertaining to details and economies of construction and operation will definitely appear from the detailed description to follow.

We accomplish the objects of our invention by the devices and means described in the following specification. The invention is clearly defined and pointed out in the claims.

A structure which is a preferred embodiment of our invention is clearly illustrated in the accompanying drawing forming a part of this application, in which:

Fig. I is a perspective view of a door latch handle embodying the features of our invention.

Fig. II is a detail view partially in section on a line corresponding to line 2—2 of Fig. I.

Fig. III is a cross section on a line corresponding to line 3—3 of Fig. II.

In the drawing the sectional views are taken looking in the direction of the little arrows at the ends of the section lines and similar numerals of reference indicate similar parts in all of the views.

Referring to the drawing, we have not shown the latch proper as its relation to the spindle will be well understood by those skilled in the art. 1 represents the door and 2 the door plate which has an opening 3 for the spindle 4. This spindle is of rectangular cross section to engage the latch. The tubular spindle housing 5 has an enlargement or annular shoulder 6 in bearing engagement with the face plate. This sleeve projects

into the bearing member 7, these parts being retained in assembled relation by the lugs 8 struck out from the spindle, the lugs engaging the flanged end of the bearing member.

The outer end of the spindle is reduced at 9 to receive the handle bar 10 which is

retained thereon by riveting or upsetting the end of the spindle at 11, the handle bar being counter-swung to receive the upset head. The front edges of the handle bar are beveled as at 12.

The face plate 13 may be of any desired material although we preferably employ colored celluloid or other material which may be made to correspond in color with the finish of the automobile body. The edges of this face plate overlap the beveled edges of the handle bar and are clamped thereon by the flanges 14 of the ornamental casing 15. This casing may be of sheet metal with a suitable finish as nickel or brass, or it may be of silver in more expensive work.

The rear finishing plate 16 is arranged upon the rear side of the handle bar and clamped thereon by folding the edges 17 of the casing thereon. The edges 18 of the rear finishing plate are inwardly offset so that when the edges 17 are folded thereon the face of the finishing plate is flush with the flanged edges of the casing.

By this arrangement of parts we provide a structure which is very economical in its parts and in assembling. At the same time it is attractive in appearance and may be easily finished to meet particular requirements.

Having thus described our invention, what we claim as new and desire to secure by Letters Patent is:

The combination of a door plate having a spindle opening therein, a spindle, a handle bar rigidly attached to the outer end of said spindle, a housing sleeve arranged on said spindle between said handle bar and door plate and having an annular enlargement engaging said plate, an ornamental face plate for said handle bar, a casing for said handle bar having flanges on its front edges overlapping said face plate, and a rear finishing plate through which said spindle sleeve is disposed, the rear edges of said casing being folded over the edges of said rear finishing plate.

In witness whereof we have hereunto set our hands.

ISAAC S. KEELER.
ALBERT L. BIRDSALL.
